UNITED STATES PATENT OFFICE.

RALPH E. RACE, OF MANSFIELD, OHIO.

LAMP.

Application filed May 31, 1923. Serial No. 642,426.

This invention is directed to an improvement in lamps or lighting means involving the use of a light source and a reflector, and designed to provide means for controlling 5 the direction and diffusion of the projected light rays.

The improved lamp includes a reflector mounted for tilting movement and designed to be fixed in any desired tilted or angular 10 position, and a light source which is permanently beyond the central or axial line of the reflector, and is in turn capable of adjustment at will to vary its angular relation to the axial line of the reflector.

15 The invention is illustrated in the accompanying drawings, showing the preferred form of the invention, and in which:

Fig. 1 is a sectional view through the improved lamp.

20 Fig. 2 is a section on line 2—2 of Fig. 1.

Fig. 3 is a broken perspective view of a portion of the adjusting member.

The invention, which is here shown as adapted for an automobile lamp, comprises 25 a casing 1 of usual shape, having an edge flange 2. A carrier rim in the form of a cylindrical extension 3 has an annular flange 4, formed with a channel 5 to receive the usual cover-ring packing 6, this rim 3 having a rearwardly extending flange 7, slotted 30 at 8, to receive bolts 9, passing through the flange 2 of the casing, and secured by nuts 10. The carrier rim or cylindrical extension is thus adjustable toward and from the casing, and may be held in any fixed relation 35 thereto, as will be obvious.

A reflector 11 is arranged within the casing, being hingedly supported at the upper portion, through the medium of a hinge 13, 40 secured in part to a bar 14 carried by the reflector and to one of the bolts 9. The lower portion of the reflector diametrically opposite the hinge is provided with a finger projection 15, adapted to seat loosely in a slot 45 16 in the flange 7 of the carrier rim. Thus as the carrier rim is adjusted, the reflector may be given any degree of tilt or inclination desired, and fixed against movement in such position.

50 The light source comprises a bulb 17, and conductor 18, the base 17' of the bulb being adapted for removal connection in the usual socket 19, longitudinally adjustable in a sleeve 19', through the conventional means, 55 including an arm 20, secured to the socket and projecting through a slot in the sleeve,

with a screw 21, mounted in the casing having threaded engagement with such arm. A spring 22 encircles the screw between the casing and arm, for insuring movement in 60 the arm and socket as the screw in a direction to increase the distance of the bulb from the reflector.

The reflector is formed with an opening 23, through which the light source or its 65 mounting projects. This opening is of materially greater diameter than that of the mounting, to permit obvious independent movement of the light source. This opening is arranged beyond, that is above or 70 below the axial line of the reflector, that is the light source is out of the true focal plane of the reflector, and remains beyond the true focal plane of the reflector at all 75 times.

The cover rim 24, having the usual glass, preferably plain to avoid light interference, is secured by the usual bayonet slot connection with pins 25, carried by the carrier rim flange 7. The glass of the cover bears 80 against the packing 6 to exclude dust.

The reflector tilted to desired position serves to throw the light rays downwardly and forwardly to avoid the glare in the faces of approaching motorists, while the 85 permanent non-focal arrangement of the light source tends to a diffusion of the light rays for more properly spreading the light projected. The adjustment of the light source is without interference from the reflector, nor does the tilting of the latter 90 affect the light source, owing to the enlarged opening 23.

The reflector may be tiltingly adjusted through movement of the carrier rim, as 95 will be obvious, though it is to be understood in this connection, that if a permanent degree of reflector tilt has been determined on as satisfying conditions and legal requirements, then the adjustment described 100 may be dispensed with, and the finger 15 permanently secured to the flange of the carrier rim, and the latter fixed securely to the casing rim, without any possible adjustment.

105 The feature of the invention considered of particular importance is the arrangement of the light source out of the focal, that is axial line of the reflector, and the tilted reflector cooperating with a light source so 110 arranged. Thus a fixed downwardly-directed and properly diffused light is

secured from the lamp, with objectionable glare entirely eliminated.

Having thus described the invention, what is claimed as new, is:—

5. 1. In a lamp, a casing having a cylindrical flange, a cylindrical extension fitting within said flange, means for adjustably connecting the flange and extension, a reflector within the casing and hingedly connected to the flange, said reflector opposite such hinged connection having an extension projecting through an aperture in the cylindrical extension, whereby when the cylindrical extension is moved relative to the flange of the casing the reflector is tilted.
10. 2. In a lamp, a casing having a forwardly-projecting edge flange, securing bolts mounted at diametrically-opposed points therein, a cylindrical extension fitted with said flange and formed with slots to

engage said bolts, a reflector hingedly connected to one of said bolts and having an extension to fit within an opening in the cylindrical extension adjacent the other bolt, whereby in the adjustment of the cylindrical extension on said bolts the reflector is tilted. 25

3. A lamp including a casing, a lens therefor, said casing having a flange, a cylindrical extension adjustably connected to said flange for movement axially of the casing, a reflector hinged to the casing at one diametric terminal and formed at the opposite terminal with a projection to seat in an aperture in the cylindrical extension, said extension being projected toward and into holding contact with the lens. 30

In testimony whereof I affix my signature.

RALPH E. RACE.
